UNITED STATES PATENT OFFICE.

JOHN EATON, OF SCHENECTADY, NEW YORK, ASSIGNOR TO GENERAL ELECTRIC COMPANY, A CORPORATION OF NEW YORK.

ELECTROMAGNETIC SWITCH.

1,166,339.

Specification of Letters Patent. Patented Dec. 28, 1915.

Application filed August 4, 1913. Serial No. 782,794.

To all whom it may concern:

Be it known that I, JOHN EATON, a subject of the King of Great Britain, residing at Schenectady, in the county of Schenectady, State of New York, have invented 5 certain new and useful Improvements in Electromagnetic Switches, of which the following is a specification.

This invention relates to electromagnetic 10 switches, and has for its object the provision of a device of this character in which the contacts cannot stick or "freeze" together under the most trying conditions of service.

15 In the operation of electromagnetic switches, especially as used in the control of electric motors where the switches are operated very frequently and the currents are heavy, it occasionally happens that the 20 arc formed between the contacts fuses the metal and causes the contacts to stick together, due to the formation of a slight weld between them. This most frequently happens where the magnetizing winding is 25 only instantaneously energized so as to cause the contacts to just touch each other without being actually forced into firm engagement. It also sometimes happens because of the slow opening of the contacts 30 due to very slow decrease of magnetic pull and other causes. In the type of contact for electromagnetic switches now well known, in which the contacts slide or roll upon each other so as to produce a wiping 35 action, any slight welding or sticking will be overcome by the wiping action if the contact is once "wiped home." If, however, the contacts merely engage or "kiss" without being wiped to the final position, 40 a weld might form which would hold the contacts in closed position against the tendency of gravity or a spring to open the switch.

One of the objects of my invention is 45 to overcome this difficulty and make it practically impossible for the contacts of the switch to weld together in the manner above described.

In carrying out my invention I provide 50 means whereby just before the movable contact reaches the fixed contact a spring is placed under stress, tending to force the movable contact away from the fixed con-

tact so that in case the contacts merely touch and tend to weld, the spring will 55 force the contacts apart and break the weld. This I have accomplished in one embodiment of my invention by the use of the spring which is ordinarily used upon such switches for causing a yielding and wiping 60 action of the contacts.

Other objects and purposes of my invention will appear in the course of the following specification in which I have shown my invention embodied in concrete form for 65 purposes of illustration.

In the accompanying drawing, Figure 1 represents a side view of an electromagnetic switch embodying my invention; and Fig. 2 a fragmentary view showing the parts in 70 a different position.

Referring to the drawings, it will be seen that I have shown an electromagnetic switch, the parts of which are of well known design, consisting of a magnetizing winding 75 10 having a magnetic frame including the core 11 and the plates 12 and 13 mounted upon an insulating base 14. Pivoted to the plate 12 is an armature member 15 co-operating with the upper end of the core 11. 80 Pivoted to this armature member at 16 is a contact member comprising a contact arm 17 upon which is mounted the contact tip 18. This tip 18 co-operates with a fixed contact tip 19 mounted upon the base 14. A 85 spring 20 is interposed between the member 15 and the contact arm 17 so that when the contact 18 engages the contact 19 the spring will yield. In the particular switch illustrated, the arrangement is such that as the 90 contacts 18 and 19 engage each other, the spring 20 is compressed and the contacts roll upon each other to a certain extent until they reach the final position shown in full lines in Fig. 1. It will be understood, of 95 course, that my invention is not limited in its application to a switch having contacts arranged in this or any other specific manner. The armature member 15 is so arranged that it is normally biased to open 100 position, this tendency to open being caused by the presence of the tail piece 15', so that when the magnetizing winding is deenergized the parts assume the position shown in dotted lines in Fig. 1. If during the 105 operation of this switch the winding 10

should be energized instantaneously, it might happen that the contacts 18 and 19 would merely touch each other and not be fully closed or wiped home. This action 5 might cause an arc which would weld the contacts and prevent their opening in response to the bias; and serious results might follow from failure of the switch to open. In order to overcome this difficulty, I provide 10 means for stopping the free movement of the contact just before it reaches the fixed contact, thereby causing the last increment of travel toward the fixed contact to be in opposition to the stress of the spring 20. In 15 the particular arrangement shown in the drawings this result is brought about by an arm 21 projecting upward from the contact arm 17 and engaging the adjustable stud constituting a stop 22. In Fig. 2 the parts 20 are shown in the position in which the contact 18 still has a short distance to travel. At this point it will be seen that the free movement of the contact arm is stopped by the engagement of the arm 21 with the stop 25 22. Further movement of the contact 18 must be against the tension of the spring 20, that is, the armature member 15 will be pulled down by the winding and the spring 20 placed under compression to force the 30 contact 18 against the fixed contact during the short distance traveled by the contact 18 which is indicated in Fig. 2; therefore the contact 18 is strongly spring pressed or biased away from the fixed contact 19 during 35 this interval. The result is that in case the contacts should get near enough to each other to form an arc and weld the contacts without forcing them to full closed position or should the contacts leave each other so 40 slowly as to arc and weld together the stress of the spring 20 would be sufficient to break the weld and allow the contacts to open. When, however, the contact 18 is forced into 45 engagement with the contact 19 to fully close the switch, the contact 18 will roll upon contact 19 and the upper end of the arm 21 will move away from the stop 22, as shown in full lines in Fig. 1. When this happens the spring 20 will operate in its normal way, 50 namely, to force the contact 18 into engagement with the contact 19. It will thus be seen that the spring 20 has a double function: first, to bias the contact 18 away from the fixed contact during its last increment of 55 travel toward the fixed contact, and second, to yieldingly hold the contacts together after the contacts once start to fully close.

While I have described my invention as embodied in concrete form and as operating 60 in a specific manner in accordance with the provisions of the patent statutes, it should be understood that I do not limit my invention thereto, since various modifications thereof will suggest themselves to those 65 skilled in the art without departing from

the spirit of my invention, the scope of which is set forth in the annexed claims.

What I claim as new and desire to secure by Letters Patent of the United States, is:

1. An electromagnetic switch comprising a magnetizing winding, an armature member having a contact resiliently mounted thereon, a fixed contact, and means whereby the resiliency of said mounting tends to force the movable contact away from the fixed contact just prior to its engagement with the fixed contact and thereafter resiliently holds it in engagement with the fixed contact when the armature member is moved to its final position by said winding. 70 75

2. An electromagnetic switch comprising a magnetizing winding, an armature member provided with a contact pivotally mounted thereon, a spring interposed between said contact and said member, a fixed contact, 80 and means whereby said spring tends to force the movable contact away from the fixed contact just prior to its engagement with the fixed contact and thereafter yieldingly holds it in engagement with the fixed 85 contact when the armature member is moved to its final position by said winding. 90

3. An electromagnetic switch comprising a magnetizing winding, a fixed contact, a contact arranged to move into engagement with the fixed contact upon the energization of the said winding, a spring acting upon said movable contact, and means whereby said spring tends to force the movable contact away from the fixed contact prior to its 95 engagement with the fixed contact and thereafter yieldingly holds it in engagement with the fixed contact when the movable contact is moved to final position by said winding. 100 105

4. An electromagnetic switch comprising a magnetizing winding, a fixed contact, an armature member having a contact movably mounted thereon and arranged to engage said fixed contact and move upon it in a direction substantially at right angles to the direction of movement of the movable member, and means whereby the movable contact is biased away from the fixed contact when the armature member is near its final 110 position and is biased toward the fixed contact when it is moved upon the fixed contact by the further pull of the magnetizing winding. 115

5. An electromagnetic switch comprising a magnetizing winding, a fixed contact, an armature member having a spring pressed contact movably mounted thereon and arranged to engage said fixed contact and move upon it against the spring pressure in a direction substantially at right angles to the direction of movement of the armature member, and means whereby the spring is placed under stress when the movable contact is near the fixed contact so as to give 120 125 130

it a spring pressure away from the fixed contact said pressure being removed by the engagement of the contacts.

6. An electromagnetic switch comprising a magnetizing winding, a fixed contact, an armature member having a spring pressed contact movably mounted thereon arranged to be moved by said winding into engagement with said fixed contact under yielding pressure of said spring, and means whereby the free movement of the movable contact is stopped when it approaches the fixed contact so that further movement toward said contact takes place in opposition to the tension of the spring.
- 10 7. An electromagnetic switch comprising a magnetizing winding, a fixed contact, a

contact arranged to move into engagement with the fixed contact upon the energization of said winding, a spring acting upon one 20 of said contacts, and means whereby said spring tends to force the movable contact away from the fixed contact prior to its engagement with the fixed contact and thereafter yielding holds it in engagement with 25 the fixed contact when the movable contact is moved to final position by said winding.

In witness whereof, I have hereunto set my hand this first day of August, 1913.

JOHN EATON.
